(57) CLAIM

The ornamental design for a power bank, as shown and described.

DESCRIPTION

FIG. 1 is a perspective view of a power bank, showing my new design;

FIG. 2 is a top view thereof;

FIG. 3 is a bottom view thereof;

FIG. 4 is a right view thereof;

FIG. 5 is a left view thereof;

FIG. 6 is a back view thereof; and,

FIG. 7 is a front view thereof.

The broken lines in the drawings are for the purpose of illustrating unclaimed portions of the power bank and form no part of the claimed design.
